US0D1063077S

(12) **United States Design Patent** (10) **Patent No.:** **US D1,063,077 S**
(45) **Date of Patent:** **** Feb. 18, 2025**

(54) **DENTAL IMAGING ATTACHMENT FOR A SMARTPHONE**

(71) Applicant: **Align Technology, Inc.**, San Jose, CA (US)

(72) Inventors: **Shai Farkash**, Hod HaSharon (IL); **Yossef Y. Atiya**, Modin-Maccabim-Reut (IL); **Maayan Moshe**, Ramat HaSharon (IL)

(73) Assignee: **Align Technology, Inc.**, San Jose, CA (US)

(**) Term: **15 Years**

(21) Appl. No.: **29/780,745**

(22) Filed: **Apr. 26, 2021**

(51) LOC (15) Cl. **24-02**

(52) U.S. Cl.

USPC **D24/176**

(58) **Field of Classification Search**

USPC D24/107, 152, 158, 176, 137; D14/217, D14/253

CPC ... A61B 1/05; A61B 1/00194; A61B 1/00172; A61B 5/1079; A61B 5/0088; A61B 5/4547; A61C 1/088; G06T 2207/30036

See application file for complete search history.

(57) **CLAIM**

The ornamental design for a dental imaging attachment for a smartphone, as shown and described.

DESCRIPTION

FIG. 1 is a top perspective view of a dental imaging attachment for a smartphone;

FIG. 2 is a back elevation view thereof;

FIG. 3 a front elevation view thereof;

FIG. 4 a right side elevation view thereof;

FIG. 5 is a left side elevation view thereof;

FIG. 6 is a bottom plan view thereof;

FIG. 7 is a top plan view thereof; and,

FIG. 8 is a bottom perspective view thereof.

The broken lines shown in the drawings are for the purpose of illustrating environmental structure and form no part of the claimed design.

1 Claim, 8 Drawing Sheets
